UNITED STATES PATENT OFFICE.

SHERMAN C. ROBERTS, OF WICHITA, KANSAS.

HAY-GRINDING MACHINE.

1,027,765.

Specification of Letters Patent.

Patented May 28, 1912.

Application filed April 5, 1910, Serial No. 553,583. Renewed October 10, 1911. Serial No. 653,966.

To all whom it may concern:

Be it known that I, SHERMAN C. ROBERTS, citizen of the United States, residing at Wichita, in the county of Sedgwick and 5 State of Kansas, have invented certain new and useful Improvements in Hay-Grinding Machines, of which the following is a specification.

This invention comprehends certain new 10 and useful improvements in mills of that type designed particularly for use in grinding hay or the like, so as to provide a comminuted product that is susceptible of being fed to cattle, or utilized for various other 15 purposes.

The invention has for its object an improved machine of this character which embodies a concave and a cylinder rotating therein, and in which the concave is composed 20 of a plurality of screen sections through which the reduced material passes. The screen sections are supported in a peculiar manner, so as to be susceptible of being removed with facility to admit of their replacement by new sections or sections of a 25 larger or smaller mesh, one of said screen sections being arranged to be adjusted toward or away from the cylinder to adapt itself to the quantity and condition of the 30 material fed into the machine.

With this and other objects in view that will more fully appear as the description proceeds, the invention consists in certain 35 constructions and arrangements of the parts that I shall hereinafter fully describe and then point out the novel features thereof in the appended claims.

For a full understanding of the invention and the merits thereof and to acquire a 40 knowledge of the details of construction, reference is to be had to the following description and accompanying drawings, in which:

Figure 1 is a transverse section of a mill constructed in accordance with my invention; Fig. 2 is a similar view thereof showing the top screen section and its supporting bars swung over into an inoperative position; Fig. 3 is a detail sectional view on the line *b*—*b* of Fig. 1.

Corresponding and like parts are referred 50 to in the following description and indicated in all the views of the drawings by the same reference characters.

My improved mill consists essentially of a 55 cylinder, A, which is supported upon the

framework of the machine, so as to be susceptible of rotation about a longitudinal axis, and which may be driven by any suitable means (not shown), the cylinder being partly inclosed by and arranged in operative relation to a concave, B. The concave, B, extends about three-fourths of the way around the cylinder and is constructed in a plurality of substantially duplicate segmental sections, each of which embodies a transversely curved frame 7, to which the meshed fabric 8 is applied. Two or more of these sections, designated 9, constitute the lower substantially semicylindrical portion of the concave and are slidably fitted at their opposite ends in semi-circular channels or grooves 10 formed in the opposing faces of a pair of curved supporting bars 11. A pair of curved supporting bars 13 are pivotally connected at one end, as indicated at 15, to the rear ends 70 of the respective supporting bars 11. The supporting bars 13 are formed in their opposing faces with curved channels 12 in which the opposite ends of the upper section 9^a are slidably fitted, said section being supported at the rear side of the cylinder and curving forwardly above the same in its operative position, as illustrated in Fig. 1. The upper or forward edge of the section 9^a normally lies in a vertical plane through the 75 axis of the cylinder and is spaced from the upper edge of the forward section 9, so as to afford a mouth through which the hay or similar material may be fed in any suitable manner. Such material first passes between the upper section 9^a and the cylinder and is then carried around by the latter to the lower sections 9 of the concave through which it falls after having been reduced by the action 80 of the teeth 9^b on the cylinder A, attention being particularly directed to the fact that the concave is disposed somewhat spirally in respect to the axis of the cylinder with the upper portion 9^a considerably spaced therefrom to accommodate the material in its 85 bulky condition, the concave gradually approaching the extremities of the teeth, so as to hold the material in close relation thereto as it becomes comminuted.

The section 9^a is preferably equipped at 100 its forward edge with a metallic plate or the like which constitutes a baffle 14 to prevent hard substances from entering the machine as would, of course, result in damage thereto.

The supporting bars 13 are formed above their pivoted ends with one or more outstanding slotted ears 16, screws 17 being inserted through the slots and engaged with 5 the framework of the machine to hold said bars against turning movement and to maintain the concave section 9^a in different adjusted positions with respect to the cylinder to compensate for the quantity and condition of the material fed into the machine. 10 The channels 10 and 12 open outwardly at the pivoted ends of the supporting bars, but are closed at their other or remote ends. In the operative position of the concave the 15 open ends of the adjacent channels are arranged in registry, so that one channel forms a continuation of the other and the concave sections are thus retained in the channels against removal. By removing 20 the screws 17 the bars 13 may be swung over backwardly about their pivots 15, so as to throw the said channels out of registry, whereby the screen sections may be withdrawn therefrom, as may be desirable to admit of their replacement by screen of larger 25 or smaller mesh, or by new sections in event of damage.

Among the many advantages attained by 30 constructing the concave in sections, it is to be observed that should one of the sections become damaged, such section may be conveniently removed and repaired or replaced by a new one, since the parts are readily interchangeable, thereby effecting a material 35 economy over the ordinary machines having the concaves all made of one piece, which latter machines must have the entire concave repaired in event of damage, at a great expenditure of time and labor.

40 It will here be noted that the seating grooves in the stationary bars 11 open through the rear ends thereof only, while the seating grooves in the movable bars 13 register with the grooves in the stationary 45 bars so that when the movable bars are swung in the direction of the cylinder, the ends of adjacent screen sections will abut and prevent accidental displacement thereof and when the fastening devices 17 are removed and the movable bars 13 swung laterally to inoperative position, the screen sections of both the upper and lower set of bars may be readily removed. It will also be noted that the member 14 not only forms 50 a baffle plate, but also serves to connect the forward ends of the movable bars 13 and at the same time forms a closure for the forward ends of the segmental slots in said movable bars.

Having thus described the invention what 60 is claimed as new is:

1. In a grinding mill, the combination with a cylinder, of spaced stationary bars surrounding the lower portion of the cylinder and having segmental seating grooves 65 formed therein and opening through the rear ends of said bars only, movable bars surrounding a portion of the top of the cylinder and having their rear ends pivotally connected with the stationary bars and their forward ends spaced from the forward ends of said stationary bars to form a feed opening at the front of the cylinder, said movable bars being provided with segmental seating grooves closed at their forward ends 70 and communicating with the grooves of the stationary bars at their rear ends, removable screen sections seated in the grooves of the stationary and movable bars, and means for adjusting the movable bars laterally with 75 respect to the cylinder.

2. In a grinding mill, the combination with a cylinder, of spaced stationary bars surrounding the lower portion of the cylinder and having segmental seating grooves 85 formed therein and opening through the rear ends of said bars only, movable bars surrounding a portion of the top of the cylinder and having their rear ends pivotally connected with the stationary bars and their forward ends spaced from the forward ends of said stationary bars to form a feed opening at the front of the cylinder, said movable bars being provided with segmental seating grooves registering with the seating 90 grooves of the stationary bars and having their outer walls provided with slotted ears, a baffle plate connecting the forward ends of the movable bars and seated within and forming closures for the ends of the segmental grooves of said movable bars, removable screen sections seated in the grooves of the stationary bars, a removable screen section seated in the grooves of the movable bars and having one end thereof bearing 95 against the baffle plate and its other end adapted to contact with the adjacent segmental screen section of the stationary bars, and fastening devices extending through the slots in said ears for holding the movable 100 bars in different positions of adjustment with respect to the cylinder.

In testimony whereof I affix my signature in presence of two witnesses.

SHERMAN C. ROBERTS. [L. S.]
